United States Patent Office.

FRANCIS A. STERRY, OF CANTON, MASSACHUSETTS.

Letters Patent No. 60,802, dated January 1, 1867.

IMPROVEMENT IN MEANS FOR ADJUSTING SPINDLES IN RING SPINNING.

The Schedule referred to in these Letters Patent and making part of the same.

TO ALL WHOM IT MAY CONCERN:

Be it known that I, FRANCIS A. STERRY, of Canton, in the county of Norfolk, and State of Massachusetts, have invented a new and improved Adjustable Spindle for Spinning Frames; and I do hereby declare that the following is a full, clear, and exact description thereof.

The object of my invention is to obviate the difficulties which have hitherto been experienced in keeping the spindle of "ring spinning frames" plumb, in consequence of the wearing away of the spindle bolster and step; and the invention consists in providing for the adjustment of both the spindle bolster and the spindle step, and in securing them in any desired position, as will be hereinafter described. And to enable others skilled in the art to make and use my invention, I will proceed to describe its construction and operation, reference being had to the accompanying drawing, which forms a part of this specification, and to the letters of reference marked thereon.

Figure 1 represents a longitudinal section of a spinning frame, partly sectional.

Figure 2 is a top view of the ring on the ring rail.

Similar letters of reference indicate like parts.

A is the step rail; B is the bolster rail; C is the ring rail; D D are the standards; and E is the spindle. F is the bolster; G is the step; H is the ring. In this example of my invention the ring rail, C, is made fast to the top of the standards, D D, which extend up through and above the bolster rail for that purpose. This arrangement is only for convenience in demonstrating my invention, as it is well known that the ring-rail is attached to lifting-rods, which give it a vertical motion when the frame is in use. The difficulty which has hitherto been experienced has been in keeping the spindle plumb and in the centre of the ring, H, which is placed in the centre of the ring rail. This ring is fast in the rail, and usually secured by a set-screw. In order that the thread from the spindle may run in the proper direction, and to avoid extra labor, it is necessary that the spindle should stand plumb and in the centre of the ring; otherwise the thread is liable to break, and the spinning is thereby interrupted. The band on the pulley, b, by which the spindle is driven, is constantly pulling the spindle in one direction, and the bolster (which is the spindle-box) is consequently worn on one side only; and as the bolster wears, the spindle is thrown out of plumb and out of the centre of the ring. This makes the trouble and causes the extra labor. The same cause is constantly operating on the bottom end of the spindle, wearing the step on one side, and consequently throwing the spindle out of plumb and from the centre of the ring, thereby causing the same trouble as before mentioned. Under these circumstances the usual remedy is to put in a new bolster, or a new step, or both. Now, I obviate the difficulty without doing either, by simply adjusting the spindle to its true position, with the same bolster and the same step, in the following manner: The bolster, F, has a broad shoulder, a', which rests upon the top of the rail, B. The lower portion, or end below the rail, has a nut, f, on it. That portion of the bolster which rests in the hole through the rail is made smaller than the hole, which allows the bolster to be moved and the spindle to be adjusted in any desired position; and when the spindle is placed in the centre of the ring, H, the bolster is secured in its place by the nut, f. The step, G, is constructed in the same manner, with a shoulder, to rest on the rail, and a nut, g, on its bottom end, under the rail. The central portion has room for adjustment in the hole, through the rail, the same as the bolster, and it is secured in its position in the same manner by the nut, g. The space around the bolster and around the step, which allows of this adjustment, is indicated by o in the drawing. p is a collar or flange on the spindle, upon which the spool rests, and the pins, o', enter the bottom end of the spool, and couple the spool to the spindle.

Having thus described my invention, what I claim as new, and desire to secure by Letters Patent, is—

Adjusting the spindle E, by the bolster F, the step G, nuts f g, and openings O O, substantially in the manner and for the purposes herein set forth.

The above specification of my invention signed by me this 5th day of September, 1866.

FRANCIS A. STERRY.
